RACE GAME APPARATUS

Bradlee W. Williams and Homer S. Williams, Chicago, Ill., assignors to Bally Manufacturing Co., Chicago, Ill., a corporation of Illinois

Application July 15, 1936, Serial No. 90,743

10 Claims. (Cl. 273—86)

The present invention relates to a simulated racing game for amusement purposes, this application being an improvement over our co-pending application Serial Number 59,279 filed January 5, 1936 for Race game apparatus.

Generally, the game is of that type in which a suitable table is provided with a plurality of race-ways, in each of which is moved an appropriate racing object. The group of racing objects, when 10 the game is released for play, simultaneously leaves a starting position to be moved toward an objective or finish line. In their movement means is operative to vary the rate of travel of the several objects in a differential manner, so that it 15 will be impossible to predict which race object will win the race by first reaching the finish line. Accordingly, the maximum amusement value is created for the player who tries to guess which object will win the race.

20 In the prior application above identified the differential drive of the several race objects was controlled by electromagnetic means. While such control is effective for the purpose intended, it is relatively expensive to produce and further the 25 making and breaking of the electrical contacts creates clicking noises which to some extent detracts from the pleasure of playing the game.

The object of the present invention is to simplify this structure to the end that clicking noises 30 will be eliminated, and also materially to lessen the cost of manufacturing the game.

The main object of the present invention is to provide an improved race game apparatus.

Another object is to provide a plurality of race 35 objects endless chain or belt carriers in combination with an improved simple, and effective means for differentially varying the speed or drive of the said chains, so that the racing objects will advance toward the finish line in an unpredictable 40 manner.

Another object is to provide an improved electrically driven game apparatus and an improved mechanical control means for varying the travel of the several race objects.

45 Other important objects will be apparent to those skilled in this art as the disclosure is more fully made.

In the present practicable embodiment of the invention to be disclosed, the race objects will be 50 in the form of horses to simulate a horse race. Obviously these objects may assume other forms, such for example, as automobiles, walking race automatons, rabbits, or sail boats, and the like. In other words, the type of racing object to be 55 employed is optional, for all types mentioned, and

others, may be used with the game apparatus of this invention.

Briefly, these desirable objects are attained in an illustrative embodiment of the invention by providing a suitable cabinet, which carries a horizontal table formed with the desired number of parallel, spaced, slotted ways. At each end of the table, and on its under side, is a bracket carrying a cross shaft structure for mounting a plurality of spaced sprocket wheels. The wheels on one end of the table are idlers and those at the other end are drivers; the wheels on the respective shaft structures being aligned in pairs to carry a plurality of endless chains. These chains correspond in number with the slotted ways in the 10 table so that each chain is fixedly connected at one point with a mounting movable in a slotted 15 way for carrying a race horse or other simulated object.

An electric motor, of the reversible type is 20 geared to drive the driven shaft structure, there being operatively associated with each drive sprocket wheel a friction clutch means. The drive sprockets are free on the shaft for independent rotation and the friction means normally holds the sprocket wheels for turning with the 25 shaft to drive the chains. An improved mechanical timing mechanism includes an auxiliary, constantly driven shaft located adjacent the sprocket wheel drive shaft, said auxiliary, or timer shaft, 30 carrying timer trip disks including trips. There is a timer trip disk operatively associated with each sprocket wheel clutch to release the latter 35 at intervals for varying the movement of the chains and race objects carried thereby to make the result of the race uncertain. This mechanical control means is so constructed that its timing may be set differently from time to time, thereby 40 making it impossible to predict the cycle of operation.

The winning horse further closes another switch 45 to cause energization of an electromagnetic device to operate an appropriate switch to establish circuits to cause reverse rotation of the motor, whereupon all chains are reversely driven to return 50 all horses to their starting positions and align same in a transverse row preparatory to the start of another race. The horses, of course, do not all return together; however, the controls are so arranged that when the last horse returns to the 55 starting position the motor circuit is opened to cause cessation of its operation so that all parts come to rest preparatory to starting the next race. So much, it is believed, will suffice in giving a general view of the improved game apparatus.

In the accompanying sheets of drawings the above preferred form of the invention is illustrated in detail. In these drawings:

Figure 1 is a general bottom plan view of the game structure;

Figure 2 is a side elevational view of the game taken along the line 2-2 of Figure 1, looking in the direction of the arrows;

Figure 3 is an enlarged side elevational view, partly in section, through a race object mounting, taken along the line 3-3 of Figure 4, looking in the direction of arrows;

Figure 4 is a detail, cross sectional view, taken along the line 4-4 of Figure 3, to show the mounting of a race object on the table;

Figure 5 is a detail side view, partly in section, of the starting end of the drive chains, showing an associated idler wheel, taken along the line 5-5 of Figure 6, looking in the direction of the arrows;

Figure 6 is a similar view, showing the same parts, the section being taken along the line 6-6 of Figure 1, looking in the indicated direction;

Figure 7 is a sectional side view through the driven end of the drive chain structure, taken along the line 7-7 of Figure 8, looking in the indicated direction;

Figure 8 is an end elevational view, partly in section of the structure shown in Figure 7;

Figure 9 is a detail, side elevational view of an electromagnetic control for an illustrative type of motor reversing switch as viewed from the line 9-9 appearing in Figure 1;

Figure 10 is an enlarged, detail, transverse sectional view of the drive shaft assembly, taken along the line 10-10 of Figure 7, looking in the direction of the arrows;

Figure 11 is a similar view through the idler sprocket shaft assembly taken along the line 11-11 of Figure 5, looking in the direction indicated;

Figure 12 is a wiring diagram for the drive motor; and,

Figure 13 is a detail, elevational view, partly in section, taken substantially along the line 13-13 of Figure 2, looking in the direction indicated.

The game is housed in any appropriate cabinet 20, carrying a horizontal table 21, extending from a front wall 22 to the opposite or rear wall, as shown. In the present embodiment nine chains and a like number of race objects, in the form of simulated horse figures are to be used. As shown in Figure 1, the intermediate portion of the table 21 between its side edges, is cut out to provide a large rectangular opening 25. At its ends are mounted cross supports 26 for carrying ten longitudinally running, inverted channel strips 27 having turned lower flanges 28 to provide tracks. These channel strips are transversely spaced apart to provide nine parallel raceway slots 29 as shown in Figure 1.

Looking at Figures 3 and 4 it will be seen that nine of the channel strips respectively carry for guided, sliding movement, an elongated sheet metal slide 30 having a horizontal bottom and upturned front and rear ends 31, which ends near their upper portions are slotted as at 32 to fit and ride on the flanges 28. Each slide 30 at its mid-portion carries to one side thereof an upstanding rigid support 33, which extends upwardly through a slot 29 as shown. The upper projected end of each support 33, above the

table has securely fastened thereto, an appropriate racing object, such for example, as the simulated race horses 34 shown. It will thus be seen that ten channel strips 27 are provided to create nine slotted race ways 29. Only nine slots are formed because each support 33 is offset to one side of its channel guide strip. The tenth strip 27 is merely provided to create a balanced, symmetrical appearance.

The forward, or starting end of the board, or table 21, carries on its under side, a depending U-shaped bracket 35, which is disposed transversely. Journaled in the ends of the bracket is a transverse, horizontal idler shaft 36, which has loosely mounted thereon for independent rotation, nine sprocket wheels 37, held apart in suitably spaced relationship by collars, or spacer sleeves 38. Each sprocket wheel has respectively wrapped therearound the forward loop, of nine endless sprocket chains 39, which run horizontally below the table.

Each chain 39 carries at fixed transversely aligned points a fastening device 40 (see Figure 4) for rigidly securing the slides 30 to the upper run of the chains. The bracket 35 along its front side further carries a cross bar 41 as shown in Figures 5 and 6. This bar 41, in alignment with each slide 30, carries spaced insulator strips 42, which serve in mounting separate pairs of conductor spring arms 43, extending vertically with contact points 44 at their upper ends normally held engaged because of the spring in arms 43. Wires 45 respectively lead in parallel from the arms 43 as shown in Figures 5 and 12. One of the arms, the rear one in each pair, extends higher than its mate, said higher arm 43 carrying a bumper member 46 in the path of movement of an end wall 31 of the aligned slide 30. When the slide is in starting position the end 31 thereof engages the bumper 46 to spread the arms 43 apart to open the contacts 44 and break the circuit in which they are included, for a purpose later to appear. When the slides leave the bumper, of course, the contacts 44 automatically close.

At the winning end of the table, the same carries on its under side another transverse bracket 47, also U-shaped, and carrying as shown in Figures 7 and 8, a transverse drive shaft 48 on which are loosely mounted nine sprocket wheels 49, around which are respectively wrapped the nine drive chains 39. Around the shaft 48, adjacent a face of each wheel 49, is a friction clutch disk 50, and adjacent each disk 50 the shaft has keyed thereto, a disk 51. Each drive sprocket assembly thus includes a loose wheel 49, a loose disk 50, and a keyed disk, or wheel 51, with the friction disks 50 respectively sandwiched between a wheel 49 and wheel 51. These unit assemblies are properly spaced apart along the shaft 48 by means of spacers 52. A spring 53 between one end of the bracket 47 and the adjacent wheel 49 serves to press all units yieldably to hold the friction disks in engagement with the respective wheels 49, 51 in each assembly.

As indicated in Figure 7 each wheel 51 is provided with a circumferentially spaced series of holes 54 in any one of which may be mounted a transversely extending cylindrical pin 55, which may include a roller, if desired.

The underside of the table 21 carries a reversible type of electric motor 56 as shown in Figures 1 and 2, the motor having a shaft to drive a worm gear set 57, thereby turning the drive shaft 48 through reduction gearing 57'. 75

The depending ends of the bracket 47 carry a transverse, horizontal plate 58 as shown best in Figures 7 and 8, said plate carrying nine upright brackets 59 for pivotally mounting a series of 5 nine upright levers 60. Each lever at its upper end is formed with a bent end to provide a dog 61 adapted to be moved into engagement with the teeth on the adjacent sprocket wheels 49. Below this end 49, each lever 60 includes a cam, or wedge 10 surface 62 adapted to lie respectively in the path of movement of the pins 55 on the wheels 51.

Each lever 60 at a point midway or so between its ends has connected to it one end of a pull spring 63, the other end of which is connected to 15 a channel shaped lever 64 pivoted at 65 to a bracket 66 mounted on the plate 58, as shown. Each lever 64 includes a bight portion carrying on its under face a trip element 67 located in a position to be engaged by an improved trip wheel 20 structure presently to be described. Each lever 64 has the bight thereof stopped short of the end of the lever thereby providing a stop shoulder 68 and extended sides to span the respective levers 60.

Below the drive shaft 48 the bracket 47 journals a transverse auxiliary control shaft 69 as shown best in Figures 7 and 8 and on said shaft is a sleeve structure 70 turning always with the shaft and including nine disk wheels 71 also turning with the shaft. Each disk wheel 71 is formed with a concentric ring of spaced holes 72 any one of which is adapted to receive and firmly hold a laterally extending trip pin and roller 73.

By means of these sockets 72 the pins on the 35 several disk wheels 71 may be angularly offset relatively in any desired staggered relationship. It can now be seen that one wheel 71 is provided for each drive sprocket wheel 49 so that a control for each of the race object moving chains 39 can 40 be achieved in a manner soon to appear.

The main drive shaft 48 is driven from the electric motor 56 in the manner already described. Said shaft 48 carries at one end in a manner later to be described and as seen in Figures 1 and 8 45 a sprocket wheel 74 for rotation to drive a sprocket chain 75 that serves to drive a sprocket wheel 76 in turn driving the shaft 69 and wheels 71. Thus, the shaft 69 and wheels 71 turn in the direction of the arrow shown in Figure 7.

In the position of the parts shown in Figures 7 and 8 the sprocket wheels 49 drive the chains 39. However, when a pin trip 73 of a control disk wheel 72 engages the arm 67 of the associated trip lever 64, said lever 64 is pushed downwardly 55 causing the shoulder 68 to separate from, or leave, the associated upright lever 60, whereupon the spring 63 is operative to pull said lever 60 toward the adjacent sprocket wheel 49 to engage the dog 61 in the teeth thereof for temporarily locking 60 said wheel 49 against rotation. The associated loose friction disk 50 permits this to happen. However, the wheel 51 keyed to the shaft 48 continues to turn and eventually its pin 55 rides against the surface 62 to cam or wedge the lever 65 60 back to its position free of the wheel 49, it being understood that the release action of the control wheel 71 is only momentary since said wheel 71 continues to rotate.

As the lever 60 thus is moved to its sprocket 70 wheel releasing position the spring 63 is effective to raise the lever 64 until the shoulder 68 thereof locks with the lever 60 to hold the parts in the position shown in Figure 7. With the sprocket wheel 49 thus unlocked the friction disk 75 50 again serves to drive the same and its associ-

ated chain 39. By this means the chains 39 are moved and stopped to advance the horses carried thereby.

As shown in Figure 7 the bracket 47 carries a cross bar 77 for mounting adjacent each finishing end of the strips 27, an insulator pack 78 for carrying separate switch units, respectively comprising groups of two upright spring arms 79, each set including contacts 80 normally held 10 gapped apart by the springiness of the stock, one of the arms in each set extending above its mate to carry a bumper element 81. There are nine such switch units in the present form of the invention and each presents a bumper element 81 in the path of movement respectively of the slides 30, so that when any slide reaches the race finish line, it will engage and close the switch unit for a purpose presently to appear.

The end of the drive shaft 48 away from the motor 56 carries loosely thereon a ratchet wheel 82 (see Figure 13). Adjacent said wheel is a hub 83 keyed to the shaft 48 and including an arm 84 carrying a gravity pawl 85 and a stop 86 therefor. The hub 83 carries the sprocket wheel 74 heretofore mentioned so that it can be seen 20 that the drive through chain 75 to the counter-shaft 69 is through the ratchet wheel 82 as governed by the gravity pawl driver 85.

Each switch 79 at one side connects by means 30 of respective wires 87 with a main power line wire 88 as shown in Figure 12, while the other side of each switch connects by means of taps 89 with a wire 90 leading to an electromagnet 91. Looking now at Figures 1 and 9 it will be seen 35 that the magnet 91 is mounted on a bracket 92 suitably carried by the underside of the table 21 or the adjacent side wall of the cabinet as desired. This bracket 92 also mounts a solenoid 93 having a core operating a link 94, which at its free end is pivotally connected to an arm 95 that normally 40 is pulled by a spring 96 to back said arm against a stop pin 97 also carried on the bracket.

This arm 95 is rockably mounted on a horizontal shaft 98, the portion of the arm surrounding the shaft being enlarged as a wheel which includes a cam notch 99. This notch 99 is co-operable with the hook end on an armature 100 pivoted at 101 to the bracket 92, a spring 102 serving normally to hold the said armature away 45 from the electromagnet 91. The shaft 98 extends through the bracket 92 to carry on the other side of the bracket a disk 103, carrying spring clamps 104 for mounting a pair of tilting type mercury switches 105 and 106. These switches as will presently appear, serve to control the direction of rotation of the reversible electric motor 56 and thereby determine whether the chains 39 are to move in a direction for advancing the horses as in a race or are to run in reverse for returning the horses to their starting 50 positions. The form of reversing switch herein illustrated is merely by way of example and in practice other well known forms of switches accomplishing the desired result may be used.

A wire 90 as has been described, leads to the magnet 91 and a wire 107 leads from said magnet 91 to the mercury switch 105. A tap 108 leads from the wire 107 to the source of power adjacent the main line 88. A wire 109 leads from the switch 105 to a variable resistance 110 and thence to the motor 56. A wire 111 connects the motor 56 and main line 88. A wire 112 goes from the motor 56 and connects with one side of each of the switches 43, the other side of said switches 43 connecting with a wire 113 leading 60 65 70 75

into the other mercury switch 106. A wire 114 leads from said switch 106 to the motor 56 and the other end of said switch 106 connects by means of a wire 115 with the motor lead 112.

5 A starting button switch 116 on the front wall 22 of the cabinet connects a wire 117 with solenoid 93 and completes a circuit through wire 118 with the main line 88, there further being a tap 119 connected between the power line 108 and 10 solenoid 93. A wire 120 runs from the switch 106 to the motor 56, as shown.

This completes the detailed description of the various parts, and the manner of use and mode of operation of the improved race game apparatus will next be described.

In starting the play of the game the nine horse carriers 30 are in the starting position at the front end of the tracks 29 with all carriers and simulated horses in transverse alignment, and 20 with the respective front walls 31 of the carriers 30 pressed forwardly against the bumpers 46 to hold open all of the switches 44. In this connection it is important to keep in mind the tilted position of both mercury switches 105 and 106. 25 They are disposed for rocking movement on a transverse horizontal axis and they extend longitudinally. In starting both switches are tilted with their forward ends down and their rear ends up, the forward end, of course, being in the 29 direction of the front wall 22. The solenoid 93 and the electromagnet 91 are deenergized since they are in open circuits. Accordingly the springs 96 and 102 hold the armatures for these electromagnetic devices in positions as shown in 35 Figure 9.

The play begins when the starting switch 116 is closed, by hand or by a coin released mechanism, if desired. Closing of the starting switch 116 as best seen in Figure 12 causes the solenoid 93 to be energized, whereupon the armature 94 is operative to pull the lever 95 (see Figure 9) to rock the shaft 98 and disk 103. This tilts both switches 105, 106 together. The shoulder 97 locks with the hooked end 100 of the armature for 45 the magnet 91. The solenoid is only momentarily energized and the lock 97, 100 acts to hold the switches releasably in their newly tilted positions.

Going back now to Figure 12 when the switches 105, 106 have been tilted down at their rear ends, we find certain circuits are closed. For 50 instance, power goes through line 108, through tap wire 107 and into the switch 105, wire 109, resistance 110, to motor 56, and by tap 111 shown to wire 88 to complete a motor circuit 55 causing rotation of the motor in a direction that will drive the chains 39 to advance the horses from the starting position thereof and toward the finish line.

The motor 56 turns and its shaft through 60 worm gears 57, and reduction gearing shown in Figure 1, rotates the rear cross shaft 48. This causes all of the nine driver disks 51 to turn and through the friction means 59, each of the loose sprocket wheels 49 is driven to drive the 65 nine chains 39. As a consequence all nine carrier slides 30 leave the switches 45, causing them to open, and to advance the horses 34 toward the winning end of the track.

The horses have now started their advance. 70 As the shaft 48 turns the plate 84 also turns and when the gravity dog 85 hangs pendants from its pivot, said dog will pick up and engage the ratchet wheel 82 to turn same. It follows, therefore, that the sprocket wheel 74 also turns to 75 drive the chain 75 and the shaft 69. As the

shaft 69 turns the pin wheel disks 71 turn therewith; however, under the gravity pawl drive action the disks 71 do not turn evenly and continuously. Thus momentary stoppage of the disks 71 does occur. When a pin 73 engages and lowers a lever 64 the associated spring 63 pulls the lever 60 to engage its stop 61 in the run of the adjacent sprocket wheel 49, thus locking said wheel 49 against rotation.

It follows that the associated chain 39 stops 10 and the horse fastened thereto temporarily comes to rest to delay its progress in the race. The associated driver wheel 51 continues to turn and eventually its pin 55 engages the cam 62 to push the lever 60 back or away from the 15 sprocket wheel to free it, whereupon the friction disk 50 causes the said wheel again to be driven to advance the delayed chain and horse. When the lever 60 is thus forced back the same 20 interlocks with the lever arm 64 at the point 25 63 to releasably hold the lever 60 in its disengaged position.

By means of the pin wheels 71 each of the 30 nine levers 60 is successively released to sprocket locking position. The various angular placing 35 of the trips 73 on the disks 71 serves to make the cycle of operation difficult to determine and by changing the relative positions of these trips 73 on their wheels from time to time further 40 difficulty will be encountered by players attempting to figure the cycle of operations. The gravity pawl driver structure of Figure 13 still further makes it impossible to forecast the cycles of 45 movement of the horses because said pawl driver acts in an irregular, indeterminate manner.

In the same manner that the angular positioning of the pins 73 on the trip wheels 71 can be changed from time to time, so can the pins 55 on the disks 51 similarly be shifted to vary their order of operation. Thus, by the combination of the mechanical timers on the shafts 48 and 69 and the irregularly operable gravity pawl drive it is difficult to predict with certainty what the cycles of movement of the horses will be. This is desirable from the standpoint of player 55 interest.

Eventually, under the influence of the delayed action differential driving mechanism, one of the horses reaches the end of its raceway before any of the others. The first horse to reach 60 the winning line causes the end 31 of the carrier 30 to push against the associated spring switch bumper 81.

Let us assume that a horse in one track reaches the winning line first and closes the end switch 65 80. Instantly a circuit from lead 88, a wire 87, wire 95 sends the current to the electromagnet 91 which is connected by wire 108 to complete the circuit. The magnet 91 therefore is energized.

As shown in Figure 9, the armature for said magnet 91 is moved against the pull of its spring to free the hooker end thereof from the shoulder 99, whereupon the spring 96 pulls the lever 95 to rock the disk 103 and tilt the mercury switches 105, 106 to the position shown in Figure 9.

The switch 105 is now reversed to break the motor circuits heretofore described which caused the drive to advance the horses toward the finish line. The circuit to the motor is now as 70 follows: from wire 108, to wire 107, past switch 105 to wire 113, through closed switches 44 and wire 112 and into the motor 56. By means of a wire running from the motor and into wire 120 connection is made at the low end of switch 75

106 with a wire 114 and back into the motor 56. The lead 111 takes the motor back to the power line 88.

The reverse setting of the mercury switch 106 5 serves to effect through the circuits described, a reversal of the motor 56 and a reverse drive of all sprocket wheels 49 and the chains 39, thereby causing the carrier slides 30 with the horses to be moved back to the starting line. Reverse drive 10 of the shaft 48 does not affect the auxiliary shaft 69 since the drive pawl 85 turning reversely merely rides idly over the ratchet wheel 82.

The slides 30 now return one by one in any order at a uniform rate of travel and as they 15 reach the starting position each carrier slide in turn backs against the switches 44 to open the same. Since these switches are in parallel the motor circuit is not broken until the last horse to return, which will be the winning horse, closes 20 its switch. Thus, when the last switch 44 is closed the motor circuit is completely broken and the motor 56 stops with all carriers 30 holding open the nine switches 44 preparatory to the running of another race.

25 This completes the description of the operation and use of the improved game apparatus, and the same is now set for a subsequent play or race, when the starting switch 116 is again closed.

It is the intention to cover all changes and 30 departures from the example disclosed which do not depart from the spirit and scope of the invention as indicated by the appended claims.

What is claimed is:

1. In a race game having an elongated frame 35 carrying a transverse shaft at each end thereof, one shaft carrying a plurality of idler sprocket wheels and the other shaft carrying a like number of loose drive sprocket wheels, means for driving the latter shaft and means on said latter 40 shaft for frictionally turning the drive sprocket wheels independently therewith, race object moving chains enveloping the idler and drive sprocket wheels, movably mounted brake members provided respectively for engaging the drive 45 sprockets to hold them against rotation, movably mounted latch means provided respectively for holding the brake members in inoperative positions, the combination with said latch means of rotary trip devices respectively positioned adjacent the latch means for causing release of 50 the latch means and movement of the brake members to drive sprocket engaging positions, and respective means operatively associated with each drive sprocket wheel to cause disengagement of the brake members and their return to latched inoperative positions.

2. In a race game having an elongated frame carrying a transverse shaft at each end thereof, one shaft carrying a plurality of idler sprocket 55 wheels and the other shaft carrying a like number of loose drive sprocket wheels, means for driving the latter shaft and means on said latter shaft for frictionally turning the drive sprocket wheels independently therewith, race object moving chains enveloping the idler and drive sprocket wheels, movably mounted brake members provided respectively for engaging the drive sprockets to hold them against rotation, movably mounted latch means provided respectively for holding the brake members in inoperative 60 positions, the combination with said latch means of rotary trip devices respectively positioned adjacent the latch means for causing release of the latch means and movement of the brake members to drive sprocket engaging positions, means

for intermittently driving the rotary trip devices, and respective means operatively associated with each drive sprocket wheel to cause disengagement of the brake members and their return to latched inoperative positions.

3. In a race game having an elongated frame carrying a transverse shaft at each end thereof, one shaft carrying a plurality of idler sprocket wheels and the other shaft carrying a like number of loose drive sprocket wheels, means for 10 driving the latter shaft and means on said latter shaft for frictionally turning the drive sprocket wheels independently therewith, race object moving chains enveloping the idler and drive sprocket wheels, movably mounted brake members provided respectively for engaging the drive sprockets to hold them against rotation, movably mounted latch means provided respectively for holding the brake members in inoperative positions, the combination with said latch means of 15 a transverse auxiliary shaft disposed adjacent the drive shaft, rotary devices on said auxiliary shaft and turnable therewith, each of said devices including a trip for respectively engaging an associated latch means to free a brake member and cause its movement to drive sprocket braking position, and respective means operatively associated with each drive sprocket wheel to release the brake members and cause their 20 return to latched inoperative positions.

4. In a race game having an elongated frame carrying a transverse shaft at each end thereof, one shaft carrying a plurality of idler sprocket wheels and the other shaft carrying a like number of loose drive sprocket wheels, means for 25 driving the latter shaft and means on said latter shaft for frictionally turning the drive sprocket wheels independently therewith, race object moving chains enveloping the idler and drive sprocket wheels, movably mounted brake members provided respectively for engaging the drive sprockets to hold them against rotation, movably mounted latch means provided respectively for holding the brake members in inoperative positions, the combination with said latch means of a 30 transverse auxiliary shaft disposed adjacent the drive shaft, means for intermittently driving the auxiliary shaft from the drive shaft, trip devices turnable with said auxiliary shaft, each device respectively associated with a latch member to engage same for releasing a brake member to cause engagement of the latter with a drive sprocket wheel, and respective means for each drive sprocket wheel to release an applied brake member and cause its movement to inoperative 35 latched position.

5. In a race game having an elongated frame carrying a transverse shaft at each end thereof, one shaft carrying a plurality of idler sprocket wheels and the other shaft carrying a like number of loose drive sprocket wheels, means for 40 driving the latter shaft and means on said latter shaft for frictionally turning the drive sprocket wheels independently therewith, race object moving chains enveloping the idler and drive sprocket wheels, movably mounted brake members provided respectively for engaging the drive sprockets to hold them against rotation, movably mounted latch means provided respectively for holding the brake members in inoperative 45 positions, the combination with said latch means of a transverse auxiliary shaft disposed adjacent the drive shaft, disks respectively associated with each latch member and mounted on the auxiliary shaft to turn therewith, means 50

to drive the auxiliary shaft from the drive shaft, trips respectively disposed on the disks and positioned to disengage the respective latch members to free the respective brake members for movement to drive sprocket braking positions, and means turnable with the drive shaft and disposed respectively for releasing the brake members from the drive sprocket wheels and causing return of the brake members to latched 10 inoperative positions.

6. In a race game having an elongated frame carrying a transverse shaft at each end thereof, one shaft carrying a plurality of idler sprocket wheels and the other shaft carrying a like number of loose drive sprocket wheels, means for driving the latter shaft and means on said latter shaft for frictionally turning the drive sprocket wheels independently therewith, race object moving chains enveloping the idler and drive 15 sprocket wheels, movably mounted brake members provided respectively for engaging the drive sprockets to hold them against rotation, movably mounted latch means provided respectively for holding the brake members in inoperative positions, the combination with said latch means of a transverse auxiliary shaft disposed adjacent the drive shaft, disks respectively associated with each latch member and mounted on the auxiliary shaft to turn therewith, means to drive the auxiliary shaft, each disk provided with a ring of holes, the holes adapted for mounting a trip pin on each disk in any desired angular position, said trip pins being adapted to disengage the respective latch members to free the respective 20 brake members for movement to brake the drive sprocket wheels, and means for releasing the applied brake members and for causing return of the brake members to latched inoperative positions.

7. In a race game a drive shaft, a drive sprocket for a chain, the sprocket mounted loose on the shaft, a driver disk turnable with the shaft, means yieldably moving the sprocket against the disk, a friction member between the disk and sprocket, said disk carrying a trip pin, a spring 45 pulled brake lever pivotally mounted adjacent the sprocket and adapted to brake the sprocket, a movably mounted latch member for normally holding the brake lever in released position, the combination with said brake lever of an auxiliary shaft driven from the drive shaft, and means on said auxiliary shaft to release the latch member to cause movement of the brake lever to engage

and brake the sprocket, a driver disk trip pin serving to disengage the brake and free the sprocket and cause movement of the brake to its released latched position.

8. In a race game a drive shaft, a drive sprocket for a chain, the sprocket mounted loose on the shaft, a driver disk turnable with the shaft, means yieldably moving the sprocket against the disk, a friction member between the disk and sprocket, said disk carrying a trip pin, a spring 10 pulled brake lever pivotally mounted adjacent the sprocket and adapted to brake the sprocket, a movably mounted latch member for normally holding the brake lever in released position, the combination with said brake lever of an auxiliary 15 shaft carried adjacent the drive shaft, means for irregularly driving the auxiliary shaft from the drive shaft, and a trip device turnable with the auxiliary shaft to cause release of the latch member to cause movement of the brake lever to engage and brake the sprocket, the driver disk trip pin serving to disengage the brake and free the sprocket and cause movement of the brake to its released latched position.

9. In a race game a drive shaft, a drive sprocket for a chain, the sprocket mounted loose on the shaft, a driver disk turnable with the shaft, means yieldably moving the sprocket against the disk, a friction member between the disk and sprocket, said disk carrying a trip pin, a spring 20 pulled brake lever pivotally mounted adjacent the sprocket and adapted to brake the sprocket, a movably mounted latch member for normally holding the brake lever in released position, the combination with said brake lever of an auxiliary 25 shaft carried adjacent the drive shaft, means for driving the auxiliary shaft, a disk turnable with the auxiliary shaft, a trip on said auxiliary shaft disk positioned to engage the latch and move it to free the brake lever for movement to 30 sprocket braking position, the trip pin on the drive shaft driver disk serving to disengage the brake and free the sprocket and whereby the brake lever may move to its latched inoperative position.

10. The combination as claimed in claim 9 in which the auxiliary shaft disk is provided with a ring of holes whereby the trip thereon may be mounted in any one of said holes to alter its angular position relative to said disk.
